SAFETY RAZOR

Olaf Rasmussen, Sidney, Ohio

Application December 16, 1944, Serial No. 568,424

3 Claims. (Cl. 30—73)

1

This invention relates to improvements in safety razors particularly adapted for use in preparing patients for surgical operations.

It is among the objects of the present invention to provide a safety razor adapted to remove a thick growth of substantially long hair without becoming clogged.

A further object of the present invention is to provide a safety razor adapted to be used in hospitals for shaving patients preparatory to surgical operations requiring the removal of densely growing long hair particularly about the abdomen of the patient.

Further objects and advantages of the present invention will be apparent from the following description, reference being had to the accompanying drawings wherein a preferred embodiment of the present invention is clearly shown.

In the drawings:

Fig. 1 is a perspective view of the shaving device.

Fig. 2 is a detail sectional view of the clamp member of the device. The view is taken along the line 2—2 of Fig. 6.

Fig. 3 is an end view of the blade member of the device.

Fig. 4 is a transverse section of the guard member of the device, taken along the line 4—4 of Fig. 7.

Fig. 5 is a cross section of the assembled device, taken along the line 5—5 of Fig. 8.

Fig. 6 is an inside view of the clamp member.

Fig. 7 is a plan view of the guard member.

Fig. 8 is an end view of the assembled device.

All of the Figures 2 to 8 inclusive are shown at an enlarged scale, the Figure 1 showing the device at substantially actual size.

The numeral 20 designates the guard member of the device, detailedly illustrated in Figs. 4 and 7. It is of rectangular shape and arcuate transversely as at 21. The guard 20 has two elongated slots 22 and 23, each one adjacent to and parallel with a longer edge of the guard. Each slot terminates adjacent a shorter, arcuate edge of the guard as shown in Figs. 7 and 8. The portion 24 of the guard, between the two slots 22 and 23, is flat. It has three spaced, circular perforations 25, 26 and 27 connected together by an elongated slot 28. The lines 29 and 30 indicate the blending juncture between the flat plane of the guard portion or platform 24 and the respective arcuate ends of the guard. The longer portions of the guard between each slot and its adjacent guard edge are curved to coincide with the arcuate end portions. This is clearly illustrated in the Figs. 4 and 5.

The flat platform portion 24 of the guard has the blade 30 clamped thereupon when the shaving device is assembled for use. This blade is shaped similarly to the guard and has a central

2

perforation corresponding to the perforation comprising the spaced openings 25, 26 and 27 and the connecting slot 28 in the guard. The longer sides of the blade provide the two cutting edges 31 and 32. Normally the width of the blade from cutting edge to cutting edge is substantially equal to the distance between the two outer edges of the guard slots 22 and 23.

A clamp 40 urges the blade against the platform of the guide. As shown in the Figs. 6 and 8, this clamp 40 is of rectangular shape similar in proportions but narrower and shorter than the guard 20. In fact the clamp is narrower than the blade 30 and is shorter than the slots 22 and 23 in the guard. The inner surface 41 which engages the blade 30 when the device is assembled, is transversely arcuate as shown in Figs. 2 and 5. A projecting rib 42 extends from the inner surface on each side of a screw stud 43 which extend centrally from this inner side of the clamp. At each corner of the clamp there is provided a small lug extending from this side of the clamp, said lugs engaging the ends of the blade when the device is assembled thereby to hold the blade in proper position on the clamp. The ribs 42 and the screw stud 43 extend into and through the perforations in the blade identical to the perforations 25, 26, 27 and 28 in the guard platform 24 through which said ribs and screw stud also extend when the clamp and blade are placed upon the guard.

A means for urging the clamp toward and against the blade 30 to press it upon the guard platform 24 is provided by the member or staff 50 which is interiorly threaded at one end to receive the screw stud 43 of the clamp as shown in Fig. 5. This staff 50 forms the handle for the shaving device as shown in Fig. 1.

When the handle 50 is screwed upon the screw stud 43, the end of the handle will engage and press upon the lower surface of the platform portion 24 of the guard and the clamp in turn will be drawn toward the said platform portion to press the blade 30 thereupon.

As has been mentioned heretofore, the inner surface 41, or the surface of clamp engaging the blade 30 is arcuate as shown in Figs. 2 and 5. The curvature of this surface is of such degree that when the clamp is drawn toward the guard by operation of handle 50 so that the blade 30 is clamped against the platform 24 of the guard, the two longer edges of the clamp, engaging the blade will flex it to conform to the curvature of the clamp so that the cutting edges 31 and 32 of the blade will be moved toward their respective guard slots 22 and 23 and held a distance of no less than forty-thousandths (.040) of an inch from the inner edge of the respective guard slot. In other words, the curvature of the inner surface 41 of the clamp 40 is such that the blade

is flexed toward the guard, so that a clearance space of no less than forty-thousandths (.040) of an inch is provided between the cutting edge of the blade and its respective guard slot edge, thereby providing an ample space through which a mass of long shaven hair may pass without clogging.

As shown in Fig. 5, the blade 30 when flexed makes a line contact with the sharp outer edge of the guard platform 24 as at 44, thereby eliminating a pocket in which shaven hair could accumulate and thus cause clogging.

The outer surface 45 of the clamp 40 is transversely arcuate as shown in Figs. 2 and 5. This curvature is of such a radius that the line extensions thereof, as indicated by the dotted lines in the assembly sectional view Fig. 5, forms the limits for the cutting edges 31 and 32 of the blade 30 and the outer edges of the guard 20.

The chord of the arc between the edge 60 of the clamp 40 and the edge 61 of the guard 20, Fig. 5, is the imaginary "contact line," or the skin level when the shaving device is used. The amount of extension of the cutting edge of the blade, beyond this "contact line" or chord provides the degree of safety of the device. If the cutting edge is extended beyond the arc, designated by the dotted lines Fig. 5, then the safety factor would be greatly reduced if the blade edge is too far below or inside this contact line then the razor will not cut; however, when the cutting edge of the blade extends up to said imaginary arc line, a safe cutting portion of the blade extends beyond the chord, which has been referred to above as the "contact line" or the line assumed by the epidermis when the device is applied to a body to shave hair therefrom.

The clamp 40 and guard 20 are so designed as to include the above described safety factor and also provide the non-clogging feature of the present device which resides in the fact that ample space is provided about the cutting edge of the blade to assure free passage of severed thick and long hair and lather. The guard is so formed that the distance B, Fig. 4, between the plane of the platform 24 and the inner edge of a guard slot 22 or 23 together with the curvature of the inner surface 41 of the clamp which flexes the blade 30 when the device is assembled, cooperate to provide the clearance space C, Fig. 5, of not less than forty thousandths (.040) of an inch between the blade and guard slot edge through which the lather-hair mass may freely pass without clogging.

As shown in Fig. 8, this clearance space is extended to and around the corners of the blade and clamp. The blade and clamp being shorter than the guard slots 22 and 23, thereby provide ample space to prevent clogging of those points.

The present invention differs from well known safety razors in that it provides a much wider space between the cutting edge of the blade and between the corners of the blade and clamp than the said well known razor while still retaining the full safety factor thereof. The ordinary safety razor has its blade cutting edge lying in very close proximity to the adjacent guard portion and thus provides minute space through which the severed hair must pass and no clearance space adjacent the ends of the blade and guard. This permits passage only of comparatively short hair stubbles without clogging. However, a razor of this type cannot be used to remove long, densely growing hair because, first, it would tend to glide over a greater portion of the thick growth

of hair and due to the minute space would clog up with the few long hairs it succeeded to cut. To facilitate cutting of the longer hair by this ordinary razor and partially reducing the possibility of its becoming clogged, the razor may be adjusted to permit flexing of the blade away from its guard and thereby increase the spacing. This however destroys the safety factor of the razor by moving the cutting edge of the blade out of the proper position relative to the guard in which position the proper degree of safety is provided.

Applicant's shaving device is particularly designed that the cooperating guard and clamp are so fashioned that the blade is flexed to hold its cutting edge a substantially greater distance from the guard than in the ordinary razor while still retaining the proper and full safety factor of the ordinary razor. The greater space between the blade and guard eliminates clogging even though the shaving device is removing a dense growth of long hair.

Applicant's invention therefor features an improved shaving device capable of removing by shaving a dense growth of hair, without becoming clogged and with a full degree of safety comparable to that of the ordinary safety razor adapted only to shave short hair stubbles on the face.

While the embodiment of the present invention as herein disclosed, constitutes a preferred form, it is to be understood that other forms might be adopted, all coming within the scope of the claims which follow.

What is claimed is as follows:

1. A shaving device comprising in combination, a guard, transversely arcuate and having two slots each parallel to and adjacent a longer edge of said guard and terminating adjacent the shorter, arcuate edges thereof, the middle portion of the guard between said slots being flat the corresponding surfaces of the arcuate and flat portions of the guard being in tangency at the longitudinal center of the guard; a blade shorter than the length of the slots and wider than the middle portion of the guard, having a cutting edge at each longer side thereof, each cutting edge substantially aligning with the outer edge of a slot when said blade is in position on the flat portion of the guard; a clamp wider than the middle portion of the guard and narrower than the blade and having an arcuate surface operative to engage and urge the blade toward said flat portion of the guard and thereby flexing said blade transversely over said portion to hold each cutting edge thereof no less than forty thousandths of an inch from the adjacent edge of the guard, said clamp being narrower than and longer than the blade, yet shorter than the slots in the guard; and means for urging the clamp toward and upon the guard to clamp the blade thereupon and flex it, said means providing a handle for the device.

2. A shaving device comprising in combination, a rectangular, transversely arcuate guard having a single, elongated slot provided adjacent and parallel to each longer edge of said guard, the inner adjacent edges of the two slots defining a flat, center platform portion on the guard; a double cutting edge blade the length of which is shorter than the length of the slots, the distance between the cutting edges of the blade being substantially equal to the distance between the outer edges of the said slots; a clamp for flexing and urging the blade upon the guard platform, the blade engaging surface of said clamp

being arcuate transversely to press the blade against the outer edges of said platform and cause said blade to be bent to conform with the curvature of the engaging clamp surface whereby each cutting edge of the blade is flexed and held in spaced parallelism with its adjacent guard slot edge no less than a distance of forty thousandths of an inch, the outer surface of said clamp being transversely arcuate, the curvature being of such a degree that extension of the arc will touch both the adjacent edge of the blade and the guard edge when the clamp is in position on the guard; and means for urging the clamp to press the blade into flexed contact with the platform of the guard, said means providing a handle for the device.

3. A shaving device comprising in combination, a rectangular, transversely arcuate guard provided with two elongated slots each parallel to and alongside a longer edge thereof, the portion of the guard between said slots being flat; a rectangular blade, the two longer sides thereof providing cutting edges, the blade being shorter in length than the slots in the guard, the width of the blade being substantially equal to the distance between the two outer edges of the guard slots;

5
10
15

a rectangular clamp less in width and longer than the blade but shorter than the guard slots, said clamp having an inner surface transversely concaved, for engaging and pressing the blade upon the flat portion of the guard to flex it so that each cutting edge thereof is no less than forty thousandths of an inch from the adjacent surface of the guard slot, the outer edge of the clamp being transversely arcuate, the curvature being of such a degree that the edges of the blade and the guard lie on the extended line thereof; and means for drawing the clamp upon the guard to squeeze and flex the blade therebetween, said means providing a handle for the device.
